TELEPHONE HANDSET SUPPORT

Lyle H. Van Dyke, Dallas, Tex.

Application June 15, 1959, Serial No. 56,334

Term of patent 14 years

(Cl. D26—14)

Fig. 1 is a perspective view of a telephone handset support, showing my new design,

Fig. 2 is an end elevational view,

Fig. 3 is a side elevational view,

Fig. 4 is a top plan view, and

Fig. 5 is an underside plan view.

The dominant features of my new design are shown in full lines, a portion of the broken line shoulder strap being omitted from Figs. 2, 4 and 5 for convenience in illustration.

I claim:

The ornamental design for a telephone handset support, as shown and described.
